UNITED STATES PATENT OFFICE.

W BURKE HODGES, OF NEW HUDSON, MICHIGAN.

POTATO-SORTING APPARATUS.

1,105,327.

Specification of Letters Patent. Patented July 28, 1914.

Application filed March 21, 1914. Serial No. 826,158.

To all whom it may concern:

Be it known that I, W BURKE HODGES, a citizen of the United States, residing at New Hudson, county of Oakland, State of Michigan, have invented a certain new and useful Improvement in Potato-Sorting Apparatus, and declare the following to be a full, clear, and exact description of the same, such as will enable others skilled in the art to which it pertains to make and use the same, reference being had to the accompanying drawings, which form a part of this specification.

This invention relates to potato sorting apparatus.

It has for its object a simple arrangement of screens which not only sorts potatoes and removes the dirt, but also directs the sorted potatoes into receptacles placed for their reception.

Figure 1, is a perspective view of the device. Fig. 2, is a vertical longitudinal section. Fig. 3, is a perspective view which shows the apparatus in process of folding.

The side rails *a* are supported on the legs *b*, *b*¹, forming what might be called an open-top table. The pair of legs *b*¹ is pivoted on the inside and the pair of legs *b* is pivoted on the outside of the side rails *a*. The pairs of legs are connected by cross bars *c*. Each pair of legs when in distended position can be braced to the side rails *a* by the braces *d* held in place by the wing screw *e*.

A bag-holding bail *f* is pivoted to the pair of legs *b*¹ on the inside so that when the pair of legs *b*¹ is folded over the screens, as shown in Fig. 3, the bag-holding bail *f* may be turned over to lie within the package formed by the collapsed apparatus.

The upper screen frame *g* is hinged to the side rails *a* by the hinges *h* which are located at the open end of the frame. At the opposite end the screen frame is provided with the handle *x*. This frame is provided with a screen *i* with large meshes, hence when potatoes are shoveled in the top of this screen the small ones drop through the square openings. This is an improved way of sorting potatoes over the old method of sorting them through spaced slats, for often flat potatoes of considerable width drop through spaces between the slats. This cannot occur with the square openings.

Underneath the frame *g* is an under screen frame *j*. This frame is provided

with meshes which are much smaller than the meshes of the screen *i*. Its purpose is to allow the dirt and refuse to drop through. The under screen frame *j* is pivoted to the upper screen frame *g* by the links *k*, one at each side. To the pair of legs *b*, a spout-piece *l* is hinged and this is provided with an extending strap *m* so that when the table is in distended position the strap *m* can be brought under the lower end of the under screen frame *j*. This allows the passing of the winged screw *n* through the hole in the strap and through a hole in the lower end of the screen frame *j*. After this fastening has taken place, the under screen is pivoted to the cross bar *c*¹ of the pair of legs *b* while the upper end of the under screen frame *j* is swingingly hung from the screen frame *g* by the links *k*. These links *k* are of such a length as to dispose the screen at quite an angularity with respect to the horizontal, as is shown in Figs. 1 and 2. To each side of the under screen frame *j* is hinged a sheet metal wing *o* and to each of these wings is pivoted a wing extension *p* near the spout end. Referring to Fig. 2, it will be obvious that the wing extension *p* can be swung back to lie against the wing *o* by reason of its pivoting thereto, while the wing *o* can be dropped down across the face of the screen by reason of its hinged connection to the screen frame. (See Fig. 3). This folding arrangement is for the purpose of folding the wings upon the screen when the apparatus is collapsed. When they are held out in the position shown in Fig. 2 they form sides for a chute formed by the second screen.

Referring to Fig. 1, a pair of triangular blocks *q* will be noticed at the open end of the upper screen frame *g*. These are screwed to the frame *g* by the winged screws *r*. They may be easily removed by taking out the screws and this will allow the insertion of a screen of different sized meshes. When in place they serve to hold the screen to the frame and also serve to throw out the metal guide pieces *s*. These metal guide pieces direct the potatoes into the bag *t* that hangs upon the sharp points *u* of the bag-holding bail *f*. In Fig. 2, it will be seen that there are points *v* located on the upper cross bar of the pair of legs *b*¹ and upon these points the cloth of the bag may be impaled as well as on the points *u* of the bail. Hence the bag is held open; also the weight

of the potatoes in the bag tends to swing the bail back, as shown in the outer dotted lines of Fig. 2.

The potatoes are shoveled onto the upper screen; the handle *x* is grasped and the screen shaken by raising it slightly, then dropping it and repeating the operation several times. After this has been done several times the small potatoes will all have dropped through the openings in the screen onto the under or finer screen. The dirt and refuse drops through both screens. Inasmuch as the links *k* connect the two screens together, any shaking of the upper screen shakes the lower screen, then by tipping the screen up to quite an angle with respect to the horizontal (as shown in the dotted lines of Fig. 2), not only will the potatoes in the upper screen run down into the bag *t*, but the potatoes in the lower screen or chute, which is simultaneously tipped, will run through the spout piece *l* into a crate or other waiting receptacle (not shown). Hence by practically the same manipulations both screens may be shaken and both screens dumped.

The guide pieces *s* can be folded back through an angle of 180 degrees so as to lie flat against the inside of the side bars of the upper screen frame *g*. This allows the removal of the screen when the blocks *q* are taken out.

Referring to Fig. 3, it will be understood how the apparatus is folded together into a small package. The whole device is turned over with the top of the screen frame *g* resting upon the floor. The bail *f* is folded through approximately 180 degrees. The spout piece *l* is detached from the lower screen frame *j*. This allows the under screen frame *j* to be folded against the bottom of the upper screen frame *g*, the wings *o* having first been folded down as shown in Fig. 3 and the wing extensions *p* swung in. Then the pair of legs *b*¹ are folded down against the bottom of the upper screen frame *g* and on the outside of the under screen frame *j*. This pair of legs *b*¹ folds on the inside of the side rails *a*. Next the pair of legs *b* may be folded down on the outside of the side rails *a* as shown by the dotted arcs of Fig. 3. Before the apparatus is turned up to fold into collapsed position, the upper frame *g* may be hooked to the side rails *a* by the hooks *w*. This holds the two together so that they will not drop away from each other in inverting the apparatus. When the apparatus is folded up it may be easily carried as a package by hand or in a carriage or wagon.

What I claim is:

1. Apparatus for sorting, having in combination, an open-top table, comprising a top frame, a pair of legs for supporting said top frame, a second pair of legs for support-

ing said top frame, the two pairs of legs being foldable one pair inside the other and into the same plane with the top frame, a screen of larger mesh pivoted at one end to the top of the top frame, and adapted to rest parallel against said top frame, a screen of smaller mesh detachably pivoted to one pair of legs, and means for operatively hanging the free end of the screen of smaller mesh underneath the screen of larger mesh, the said screen of smaller mesh being of less width than the narrower pair of legs and adapted, when detached from its pivot, to lie between the narrower pair of legs in the plane of the top frame and against the screen of larger mesh.

2. Apparatus for sorting, having in combination, a pair of side rails forming the top of an open-top table, a pair of legs pivoted at one end of the side rails to the outside thereof, and foldable into the plane of the side rail at the outside of the side rails, a second pair of legs pivoted at the other end of the side rails to the inside thereof and foldable into the same plane as the side rails and within the said two side rails, a screen of larger mesh pivoted to the top of the side rails at one end and adapted to lie against the side rails, a screen of smaller mesh detachably pivoted to one pair of legs and adapted to lie against the bottom of the screen of larger mesh when detached from its pivoting and to lie between the inside pair of legs, and means for flexibly suspending the free end of the screen of smaller mesh beneath the screen of larger mesh.

3. Apparatus for sorting, having in combination, a top frame, two pairs of legs foldable, when collapsed, into the same plane as the top frame, a screen of larger mesh pivoted at one end to the top frame and adapted to lie against the top of the top frame when the apparatus is collapsed, a screen of smaller mesh suspended at its free end to the screen of larger mesh and of width narrower than the inside pair of legs, so as to lie between the inside pair of legs, and means for flexibly suspending the free end of the screen of smaller mesh beneath the screen of larger mesh.

4. Apparatus for sorting, having in combination, a top frame, two pairs of legs foldable, when collapsed, into the same plane as the top frame, a screen of larger mesh pivoted at one end to the top frame and adapted to lie against the top of the top frame when the apparatus is collapsed, a screen of smaller mesh suspended at its free end to the screen of larger mesh and of width narrower than the inside pair of legs, so as to lie between the inside pair of legs in the plane of the top frame, a spout for said screen of smaller mesh pivoted to one pair of legs and attachable to the end of the screen of smaller mesh opposite the sus-

pended end, and a pair of wings hinged to the sides of the screen of smaller mesh and foldable over against the said screen, when the apparatus is collapsed.

5 5. Apparatus for sorting, having in combination, an open-top table comprising a top frame supported upon legs, an upper screen frame provided with a screen of large mesh, said upper screen frame being pivoted at 10 one end to the top frame and adapted to rest thereupon in horizontal position except when operated by swinging in a vertical arc and striking the same against said top frame, an under screen frame provided with 15 a screen of finer mesh pivoted at its end which lies opposite the pivoted end of the

upper screen frame and underneath the table, and a link for holding the free end of said under screen higher than the pivoted end and to the upper screen frame adjacent 20 the upper screen frame's pivoted end, whereby manipulation of the upper screen frame serves to shake the lower screen frame and the bringing of the upper screen frame into an angularity for dumping its contents also 25 facilitates the dumping of the lower screen.

In testimony whereof, I sign this specification in the presence of two witnesses.

W BURKE HODGES.
